ELEVATOR CAR STOOL

Charles J. Lehn, Oak Park, Ill., assignor to Otis
Elevator Company, New York, N. Y., a corpo-
ration of New Jersey

Application September 28, 1934, Serial No. 745,927

3 Claims. (Cl. 155—32)

The invention relates to stools for elevator cars. It is common practice to furnish stools or other forms of seats in elevator cars in order that the operator may rest during periods of intermittent service. It is important that these stools shall not occupy any useful space in the elevator car when not in use, as during periods of intense service. It is also important that the stool shall not detract from the appearance of the interior of the car either when in use or when not in use. This latter feature is particularly important in modern elevator cars, which are often elaborately and artistically decorated.

According to the invention, there is provided a stool of attractive appearance when in position for use and which, when not desired for use, is lowered so that its upper surface is flush with the surface of the floor of the car. The upper surface is preferably finished with the same finish as that employed for the elevator car floor.

In order that the invention may be readily understood, it will be described in connection with the accompanying drawings, in which:

Figure 1 is a perspective view of the interior of an elevator car provided with a stool according to the invention, and shows the tool in position for use;

Figure 2 is a view in elevation of the stool and its support, and shows the stool in a position intermediate its raised and lowered positions; and

Figure 3 is a view in section of the stool, taken along the line 3—3 of Figure 2.

Referring to Figure 1, there is provided in the elevator car 1 a supporting member 2 let into the floor of the elevator car and having a recess 3 in its upper surface. The seat portion 4 has attached to it tube 5 arranged to slide in an aperture in the supporting member 2. When the stool is in position for use, it is latched in its raised position, and when not desired for use, it is lowered by hand so that the seat portion 4 rests in recess 3 with its top surface flush with the floor of the car. The upper side of the seat portion 4 is recessed to a depth equal to that of the floor covering of the elevator car. This recess is filled with material of the same design as that of the elevator car floor. This material may, for example, be linoleum or carpet.

Referring to Figures 2 and 3, the seat portion 4 may consist of an aluminum alloy casting having on its lower side a cylindrical extension 6 and an annular recess in its upper surface, which recess is filled with flooring material 7. Tube 5, preferably of steel, chrome plated and accurately

dimensioned, is slipped over the extension 6 with a press fit, so that it is securely attached to the seat portion 4. At the lower end of tube 5 one or more pins 8 (shown in the drawings as two) extend through the axis of tube 5 at right angles thereto and project at each end beyond the exterior surface thereof. The purpose of these pins is to latch the stool in its raised position at one or more different heights to accommodate operators of different stature. A pull 9 is provided for raising the stool. Pull 9 is a T-shaped member, the shank of which extends through an aperture 10 at the central point of seat portion 4. A washer 11 and cotter pin 12 retain the pull in assembled relationship to seat portion 4. The cross bar of the pull is provided with a bevelled portion 13 to afford a finger hold. As shown, the pull 9 is in the position it occupies when the stool is being raised. With the stool in either its raised or lowered position, pull 9 drops down into a recess 14 in seat portion 4, its upper surface being flush with the upper surface of seat portion 4.

Supporting member 2, preferably of an aluminum alloy, is provided with a recess in its upper surface to receive seat portion 4 and is let into the car floor 15 so that its peripheral flange 16 is flush with the surface of the floor. Supporting member 2 is secured to the floor as by screws 17. Hub 18 extends downwardly from the body portion of supporting member 2 and is bored out from its upper end to within a short distance of its lower end to receive fibre-lined steel sleeve 19, the fibre portion of which is indicated at 20. Sleeve 19 is held in place by one or more pins 21. The interior diameter of fibre portion 20 is made such that when tube 5 is moved up and down there will be sufficient friction to maintain tube 5 in any position, at the same time permitting seat portion 4 being readily moved up and down by hand. The purpose of this arrangement is to avoid any possibility of a rapid descent of seat portion 4, and consequent possible injury to the feet of occupants of the car. Hub 18 is split longitudinally along one side from its lower end to a point near the upper end so that, by means of bolts 23 passing through lugs 22, the lower portion of hub 18 acts as a clamp.

At the lower end of hub 18 there are two slots 24 diametrically opposite each other and extending from the lower end of the hub upwardly. Each of these slots has an entrance portion slightly wider than the diameter of pins 8 and then widens out, notch 25 being formed at the lower end of the widened-out portion.

As the stool is raised to its working position, upper pin 8 will enter slot 24, and if the car operator desires to have the seat portion at the lower of its two raised positions, he rotates seat portion 4 and therefore tube 5 as soon as the upper pin 8 reaches the widened portion of slot 24. Upper pin 8 is then lowered into notch 25 and the stool is securely latched in its working position. If the operator desires to have seat portion 4 in a higher raised position, he lifts seat portion 4 until lower pin 8 reaches the widened portion of slot 24 and then rotates seat portion 4 and latches the stool with lower pin 8 seated in notch 25. It is to be noted that slot 24 must be of sufficient length to accommodate as many pins 8 as are provided, and that the length of the portion 26 of the slot between the lower end of hub 18 and the edge of notch 25 must be less than the clear space between pins 8.

Although cylindrical extension 6 of seat portion 4 is shown as being centrally disposed, this extension may be placed off center to permit the supporting member 2 to be placed nearer the wall of the elevator car than as illustrated in Figure 1.

With such an arrangement the seat portion 4 is rotated away from the wall when latching it in its raised position. In addition, seat portion 4 may be made square or of any other desired configuration, in which case the recess in supporting member 2 is made to correspond. Furthermore, if it is desired to shorten the over-all length of tube 5, this tube may be made in two or more telescoping sections. Other changes in details of construction may obviously be made without going beyond the scope of the invention.

What is claimed is:

1. An elevator car stool comprising a seat portion, a downwardly extending cylindrical member attached to the underside of said seat portion, a supporting member secured to the floor of the elevator car and provided with a hub depending therefrom through the floor of said car and through which said cylindrical member extends, said supporting member being further provided with a recess in its upper surface for receiving said seat portion when the stool is not in use, and means for latching said stool in either of two raised working positions different distances from said floor, said last named means comprising a pair of supporting elements projecting from said cylindrical member at different distances from the bottom thereof, said hub being provided with a slot extending from its lower end and of a width to provide a narrow entrance for said supporting elements, said slot being widened above its entrance for a distance sufficient to receive both support-

ing elements and said narrowed portion of said slot being of such length that said cylindrical member can be rotated to move either the upper or both of said supporting elements into the widened portion of said slot, and a retaining notch formed at the bottom of said widened portion in which one or the other of said supporting elements rests to support said stool in one or the other of said two working positions.

2. An elevator car stool comprising a seat portion, a downwardly extending cylindrical member attached to the underside of said seat portion, a supporting member secured to the floor of the elevator car and provided with a hub depending therefrom through the floor of said car and through which said cylindrical member extends, said supporting member being further provided with a recess in its upper surface for receiving said seat portion when the stool is not in use, and means for latching said stool in either of two raised working positions different distances from said floor, said last named means comprising a pair of supporting elements projecting from said cylindrical member in vertical alignment at different distances from the bottom thereof and an other pair of supporting elements projecting from said cylindrical member at said different distances from the bottom thereof and diametrically opposite the first mentioned pair of supporting elements, said hub being provided with a pair of slots diametrically opposite each other and extending vertically from its lower end and of a width to provide narrow entrances for said pairs of supporting elements, each of said slots being widened above its entrance for a vertical distance sufficient to receive both supporting elements of a pair upon rotative movement of said cylindrical member, and a retaining notch formed at the bottom of the widened portion of each slot to receive and support one or the other of said supporting elements of a pair to thereby support said stool in one or the other of said two working positions.

3. An elevator car stool comprising a seat portion, a downwardly extending cylindrical member attached to the underside of said seat portion, a supporting member secured to the floor of the elevator car and provided with a hub through which said cylindrical member extends, a sleeve secured in said hub and frictionally engaging said cylindrical member, said supporting member being further provided with a recess in its upper surface for receiving said seat portion when the stool is not in use, and means cooperating between said cylindrical member and said hub for latching said stool in its position for use.

CHARLES J. LEHN.
